HAIR CLIPPER

Samuel G. Branch, Middletown, Conn., assignor
of one-third to Carl F. Peterson, Middletown,
Conn.

Application May 23, 1936, Serial No. 81,423

3 Claims. (Cl. 30—1)

My invention relates to the class of devices employed for cutting hair, and an object of my invention, among others, is to provide a device of this type that may be held in a manner similar to that for holding shears in the operation of cutting hair; and a further object of the invention is to provide a device of this class that may be readily constructed and that shall be particularly efficient in its method of operation.

One form of a hair clipper embodying my invention and in the construction and use of which the objects herein set out, as well as others, may be attained is illustrated in the accompanying drawing in which—

Figure 1 is a side view of my improved hair clipper.

Figure 2 is a view in lengthwise central section through the same.

Figure 3 is a view in cross section on a plane denoted by the dotted line 3—3 of Figure 2.

Figure 4 is a fragmentary view in lengthwise section through the handle illustrating the method of securing the stationary blade to the handle.

Figure 5 is an inside view of the detachable handle section.

Figure 6 is a detail view in cross section on a plane denoted by the dotted line 6—6 of Figure 4.

Figure 7 is a detail view in cross section illustrating the connection for the coupling plug.

While my invention is not limited in its use for cutting or clipping hair of any particular nature, yet, I have in mind its adaptability for cutting hair on the human head, my invention as embodied in such a device being shown in the drawing herein. It will be obvious however, that the clippers may be used for shearing wool or other substances in the nature of hair or wool without departing from the spirit and intent of the invention.

The device as described herein comprises a handle which is preferably formed in two sections with a blade support secured thereto and a blade reciprocally mounted in said support, means being provided in the handle for imparting reciprocating movement to the blade. The numeral 1 denotes the main section of the handle including a semi-cylindrical portion 8 comprising a body part and with a web 9 protruding therefrom on one side, this web terminating in a ring or loop 10 with a finger rest 11 in a manner common to shear construction. The body part 8 comprises substantially half of the handle as a whole and it has a recess 12 with bridges 13 extending thereacross, said bridges constituting a

portion of the bearings for a driver to be herein-after described.

The secondary handle section is similar in form to that just described and comprises a body part 14 with a recess 15, bridges 16 and a loop or ring 17. A blade support 18 is upturned at one edge to form a supporting lip 19 creating one side of a blade groove 20. This blade support is tapered from the handle to the point, somewhat to resemble shear blades when closed together. It has a tang which is secured to the main handle section 1 within an opening into the end thereof. Screws may be used for securing the blade support in place if desired, or any other suitable fastening means may be employed. The front edge of the blade support is formed with teeth 22 that may be sharpened to provide cutting edges.

A blade 23 is located in the groove within the lip 19 for reciprocating movement therein, this blade having guide slots 24 through which screws 25 extend, said screws also passing through the supporting lip 19. A lubricating groove 26 is also formed in the blade for the purpose of receiving a lubricant of a more or less thick character. The front edge of the blade is provided with teeth 27 which are spaced apart substantially the same distance as are the teeth 22 on the stationary blade section and which may be sharpened to cooperate with said last mentioned teeth.

As a means for reciprocating the blade 23 I provide a cam 28 which is located in the end of a driver 29 rotatably mounted in bearings in the bridges 13 and 16. In the construction as shown herein the cam 28 engages in a groove in the edge of the tang 21 at the inner end of the reciprocating blade, and a finger 30 on the tang projects into a cam groove 31 comprising a part of the cam, and as shown in Fig. 2 of the drawing.

The end of the driver comprising a shaft 32 is suitably formed to receive a coupling as from a flexible shaft driven by a motor of any suitable character, as herein shown the shaft having a hole in its end with a slot opening out of one side of the hole to receive a plug 33 with a spline 34 integrally formed thereon, the plug being located at the end of the flexible shaft and driven thereby, and when inserted in the socket in the shaft 32 operates to rotate the cam 28 and thereby to impart reciprocating movement to the blade 23.

The tool as illustrated herein is of particular advantage in cutting hair on the human head, as it may be held by one hand in the same manner as are a pair of shears and the comb

may be manipulated by the other hand of the operator as is customary in cutting hair with a common pair of shears. The operation of the blades in cutting hair will be readily understood by those skilled in the art.

I claim:

1. A hair clipper shaped to resemble a pair of shears when the blades thereof are closed together, said clipper comprising a handle, a stationary blade secured to the handle, a movable blade associated with the stationary blade for reciprocating action, the stationary blade being U-shaped in cross section with side walls and a bottom wall inclosing and retaining the movable blade, the said bottom wall adapted to accommodate the sliding action of the movable blade, cutting teeth on adjacent edges of the movable blade and of the stationary blade, a rotatable grooved cam mounted in the handle, 20 and a tang carried by the inner end of the movable blade, having a finger operatively extending into the groove in the cam for effecting reciprocation of the movable blade upon rotation of the cam.
25. 2. A hair clipper shaped to resemble a pair of shears when the blades thereof are closed together, said clipper comprising a handle, a stationary blade secured to the handle, a movable blade associated with the stationary blade for reciprocating action, the stationary blade being U-shaped in cross section with side walls and a bottom wall inclosing and retaining the movable blade, the said bottom wall adapted to accommodate the sliding action of the movable blade, cutting teeth on adjacent edges of the movable blade and of the stationary blade, a rotatable grooved cam mounted in the handle, and a tang carried by the inner end of the movable blade,

having a finger operatively extending into the groove in the cam for effecting reciprocation of the movable blade upon rotation of the cam, said handle carrying internal bridge pieces, a drive shaft carried by one end of the cam and 5 journaled in a bearing in a bridge piece and a reduced neck portion on the cam journaled in another bridge piece with the shoulders of the neck engaging opposite faces of the bridge piece for restraining longitudinally shifting 10 movements of the cam relative to the handle.

3. A hair clipper shaped to resemble a pair of shears when the blades thereof are closed together, said clipper comprising a handle, a stationary blade secured to the handle, a movable blade associated with the stationary blade for reciprocating action, the stationary blade being U-shaped in cross section with side walls and a bottom wall inclosing and retaining the movable blade, the said bottom wall adapted to accommodate the sliding action of the movable blade, cutting teeth on adjacent edges of the movable blade and of the stationary blade, a rotatable grooved cam mounted in the handle, 15 and a tang carried by the inner end of the movable blade, having a finger operatively extending into the groove in the cam for effecting reciprocation of the movable blade upon rotation of the cam, the mounting of the movable blade including a pin and slot connection between 20 each end of the movable blade and a side wall of the stationary blade with the slots confined between the side walls of the stationary blade and said movable blade being longitudinally slotted between the pin and slot connections and 25 said longitudinal slot adapted to receive a lubricant or the like.

SAMUEL G. BRANCH.
